UNITED STATES PATENT OFFICE.

THOMAS M. CONGER, OF ELYRIA, OHIO.

SHOCK-ABSORBING HEEL.

1,863,568.

Specification of Letters Patent. Patented Dec. 28, 1920.

Application filed May 19, 1919. Serial No. 298,210.

To all whom it may concern:

Be it known that I, THOMAS M. CONGER, a citizen of the United States, residing at Elyria, in the county of Lorain and State of Ohio, have invented a new and useful Shock-Absorbing Heel, of which the following is a specification.

My present invention relates to shock absorbing heels, the primary object being to provide a heel which will wear longer than the heels of this type and which will obviate slipping.

A further object of this invention is to provide a cushion heel which is constructed so that wear on the heel at its edges is avoided.

Another object is to provide a heel of the above type which is simple in construction, consists of few parts, and which may be manufactured and placed on the market at a minimum cost.

With the above and other objects and advantages in mind which will be enlarged upon hereinafter, the invention consists of 25 combinations of elements, arrangement of parts, formations, and general assembly which will be referred to in detail and illustrated in the accompanying drawing.

On the drawing:—

Fig. 1 is an elevation of my improved heel showing the wear face of the same;

Fig. 2 is an elevation showing the reverse face of the heel;

Fig. 3 is an end elevation of the heel looking from the forward end of the same;

Fig. 4 is a longitudinal sectional view of the heel taken on line 4—4 of Fig. 1;

Fig. 5 is a fragmentary transverse sectional view taken on line 5—5 of Fig. 1;

Fig. 6 is an enlarged fragmentary transverse sectional view taken on line 6—6 of Fig. 1 and showing the heel applied to the heel lifts; and

Fig. 7 is a modified form of the invention. Referring to the drawing wherein like characters of reference designate like parts, the numeral 5 denotes a rubber or other composition heel in general, the heel being attached to the shoe by fastenings 6.

The inner face of the heel is formed with a stepped recess 7 which terminates in a centrally disposed vacuum chamber 8 that is surrounded by a rib or beading 9. Thus,

it will be seen that the stepped recess in the upper or inner face of the heel, results in the formation of a plurality of similariv

shaped continuous beads or ribs, the same corresponding in outline as the heel, and the plurality, two as shown, of section chambers or cavities, thus formed, corresponding in outline to the outline of the heel and of the beadings formed by the ribs or beads, as described, so that the heel is more effectively secured in position. The outline of the section chambers or cavities, would however, correspond with the outline of the beadings, and since the heel is convexed on its outer or bottom face, and concaved on its inner or upper face, so as to produce the stepped recess with the resultant construction and utility as above outlined, this formation has a special function in connection with a heel having an anti-slipping wear surface and particularly with corrugations arranged as will be hereinafter more fully described. This is due to the fact that the anti-slipping surface tends to hold the heel when it strikes the floor or pavement and tends to dislodge the heel from the shoe, which possibility is prevented by the formation of the heel as above set forth.

The outer face of the heel is convex and has anti-slipping projections 9' formed at its edges. It should also be noted that the fastening means 6 pass through the heel or tread at the concavity 7, between the inner and outer beads, so that a shorter leverage is produced between the same and the outer bead, which by reason of the inner bead, results in the outer bead being held more firmly against the lift of the heel than would otherwise be possible, especially if the inner bead were omitted, owing to the distance between the fastenings and the outer bead being less so that the tread is more firmly secured in position.

Tread members 10 are formed on the heel and are disposed in divergent relation upon opposite sides of the crest of the heel and in parallel relation. The wear surfaces of these tread members are formed with parallel corrugations or ribs 11 which diverge from the crest of the heel.

From the disclosure it will be apparent that by arranging the tread members 10 and the corrugations so that the corrugations on one side of the crest of the heel diverge from the ones on the opposite side, the heel will be prevented from slipping laterally.

This embodiment of the invention is considered the preferred form but it is to be understood that the invention may be modi-

fied in many respects and that my limits of modification are governed only by the appended claims.

In the modification shown in Fig. 7, the outer surface of the heel is formed with transverse parallel grooves 11 that define tread members 12 therebetween.

What is claimed is:—

1. A cushion heel comprising a body having a stepped recess in its inner face which terminates in a centrally disposed vacuum chamber, a rib surrounding the vacuum chamber and of the same outline as the heel, the outer face of the heel being convex and a bead around the edge of the heel and forming in conjunction with said rib, a pair of suction chambers adapted to retain the heel in position.

2. A shock absorbing heel comprising a resilient body having a convexed outer face and a concaved inner face formed with a stepped recess producing a plurality of similarly shaped continuous beads producing a plurality of suction chambers or cavities therebetween, adapted when the heel is flattened or straightened out when applied, to retain the heel in position on a shoe.

3. A cushion heel comprising a resilient body having a stepped recess in its inner face forming a plurality of beads corresponding in outline to the outline of the heel and extending continuously around the same to produce a plurality of correspondingly shaped suction cavities therebetween, and

securing means passed through the heel between the beads for engagement with the shoe.

4. A cushion heel comprising a resilient body having a stepped recess in its inner face forming a plurality of beads corresponding in outline to the outline of the heel and extending continuously around the same to produce a plurality of correspondingly shaped suction cavities therebetween, and securing means passed through the heel in engagement with the shoe, said fastening means passing through the heel at the cavities between the beads, said beads being flattened at the crests or apexes thereof, when applied and secured in position.

5. A cushion heel comprising a body having a vacuum chamber in its inner face, the outer face of the body being convexed and the inner face concaved and formed with a continuous raised bead at the edge thereof, entirely around the heel and inwardly thereof also, with a bead of similar outline as the first-mentioned bead and substantially parallel thereto, to produce a pair of continuous vacuum or suction cavities, and securing means for the heel.

In testimony that I claim the foregoing as my own, I have hereto affixed my signature in the presence of two witnesses.

THOMAS M. CONGER.
